COMBINED WASTE RETAINER AND COLLAR LUBRICATOR

Charles A. Gammon, St. Augustine, Fla.

Application March 30, 1949, Serial No. 84,273

5 Claims. (Cl. 308—89)

1
This invention relates to plain journal boxes for railway cars and provides a new article of manufacture, in the form of a combined journal-collar lubricator and waste-retainer.

Journal boxes of the type mentioned are packed with oil-saturated waste so that the waste is in contact with the turning journal below the brass. Displacement of this waste has long been a source of trouble. A wide variety of retainers have been proposed and some have gone into commercial use. Many of them involve some sort of metal structure inserted into the box above the waste and designed to prevent it from working to the front of the box where it tends to pack and ultimately to force the box-lid open.

The present invention is based on the concept that the logical way to prevent movement of the waste forward is to fill the space in the lower forward part of the box with an oil-saturated form-retaining felt insert which confines the waste, and fits the box so closely that the waste cannot displace it. The insert acts inherently as a lubricator.

The contour of the space to be filled is so irregular that it is not practicable to manufacture the insert in one piece at reasonable expense. The wide variety of journal boxes further complicates this problem. Hence, partly as a measure of economy, the inserts are laminated on planes normal to the journal axis, a procedure permitting some of the layers to be cut from sheets of felt. Inasmuch as a satisfactory adhesive for connecting the felt layers has not been found the presently preferred practice is to sew the laminae together.

The rear layer of felt is relatively thin and engages behind the collar on the end of the journal, where it functions effectively as a collar lubricator.

The invention will now be described in detail by reference to the accompanying drawing which illustrates a successfully tested embodiment.

In the drawing:

Fig. 1 is a vertical axial section through a typical journal box showing the new waste retainer and collar lubricator in place.

Fig. 2 is a front elevation of the retainer removed from the box.

Fig. 3 is a left side elevation of the same.

Fig. 4 is a plan view.

Fig. 5 is a perspective view.

In the present description statements of direction will be made on the assumption that the observer is at the side of the car looking toward the end of the journal so that the "for-

ward" portion of the box and journal is that toward the observer and the "rear" portion is away from the observer and toward the wheel, it being remembered that on a railway car the

5 wheels are located between the two journals which are at the ends of the axle.

The journal box is generally represented by the numeral 11 and has an opening at 12 which is normally closed by a lid not shown in the drawing but hinged according to custom on the lugs

13. In the upper portion of the box are the brass

14 and wedge 15 which are constructed according

to accepted standards and require no description.

The axle generally indicated at 16 has a journal

17 which terminates in the usual journal collar

18. The slot indicated at 19 is for the reception

of a dust guard not illustrated in the drawing, and with which the present invention is not con-

cerned. The lower portion of the box forms a receptacle commonly called the "cellar" which contains oil-saturated waste generally indicated at 21. In the conventional journal box this waste

is the sole means for lubrication. It is commonly used without any retaining means whatsoever,

25 but when so used occasionally creeps and causes trouble by packing in the front of the box. This action is often sufficient to force the box lid open, which is harmful because it permits the

entrance of dust. Displacement of the waste in-

30 evitably impairs lubrication of the journal, and this is the primary objection.

According to the present invention there is inserted in the forward portion of the cellar a retainer which is made up of a high grade oil

35 absorbing material preferably felt or some satis-

factory substitute having physical characteristics

which resemble the characteristics of felt. A

high grade wool felt is preferred and has been

successfully used.

40 This retainer as illustrated in the drawing is made of three layers 22, 23 and 24 composed of

relatively thick felt and a fourth and thinner

layer 25 which is the rear layer and forms a flange 26 dimensioned to engage behind the jour-

45 nial collar 18. The side and bottom external con-

tours of the retainer are such as to fit closely

the internal contour of the box 11 in the forward

50 portion of the box and below the lower margin

of the opening 12.

As best shown in Fig. 2 the flange 26 is arcuate

and is adjacent an arcuate channel indicated in

Figs. 2, 4 and 5 by the numeral 27. This arcuate

channel fits the periphery of the journal collar

55 18. As viewed in Fig. 2 the retainer may be said

to have upward extending portions which conform to and embrace the journal collar.

The effect of the retainer is to confine the waste 21 in a position beneath the journal and to the rear of the collar. Since the retainer resists displacement because of its close fit, it exercises an adequate restraining action. The retainer is oil absorbent and performs the function of lubricating the journal collar. It thus becomes a part of the complete packing of the box. Since it is closely confined at the front of the box, it is not disturbed by the use of packing irons. As a consequence, the collar is effectively lubricated and because it is lubricated by the felt retainer it is protected against "waste grabs" and "lint wipers" commonly present in bearing waste. As is well known these have a tendency to accumulate on the collar end of the bearing and wedge. If they enter between the collar and the bearing as they tend to do, they cause serious trouble. Thus, the retainer also performs a useful function by keeping the waste away from the collar.

The retainer is low in first cost, is easy to insert, and because it is located in the lower portion of the box, does not interfere with inspection and servicing of the bearing.

For convenience in removing the retainer from the box it is desirable to attach a pull loop 28 which is formed of tape and which is accessible at the front of the box. This loop takes no part in the normal functioning of the retainer, and can be omitted.

I claim:

1. A waste retainer for use in plain journal boxes of the type in which the journal has a collar at its end and turns against a brass mounted in the top portion of the box, and the box has a front opening and also a cellar which is packed

with oil-saturated waste, said retainer comprising an oil-absorbent unit of felt-like material formed to fit the interior of that portion of the cellar which is forward of a plane normal to the journal axis and slightly to the rear of the journal collar, and which portion is below the lower margin of the front opening of the box, said unit having lateral upward-extending portions which conform to and embrace the journal collar, and having also a flange which enters behind the journal collar and contacts therewith, said extensions and flange terminating at levels not higher than the journal axis.

2. A waste retainer as defined in claim 1 in which the unit of felt-like material is laminated and the planes of lamination are normal to the axis of the journal.

3. A waste retainer as defined in claim 1 in which the unit of felt-like material is laminated, the planes of lamination are normal to the axis of the journal and said flange is formed by one of the laminations.

4. A waste retainer as defined in claim 1 in which the body of felt-like material is laminated, the planes of lamination are normal to the axis of the journal and the laminations comprise a thin lamina which forms the flange and a plurality of thicker laminae which form the major portion of the body.

5. A waste retainer as defined in claim 1 in which the unit of felt-like material is laminated, the planes of lamination are normal to the axis of the journal and the laminae are connected by stitches.
